UNITED STATES PATENT OFFICE.

EDWARD W. SMITH, OF PHILADELPHIA, PENNSYLVANIA.

CONSTANT-LEVEL DEVICE FOR STORAGE BATTERIES.

No. 907,419.

Specification of Letters Patent.

Patented Dec. 22, 1908.

Application filed October 4, 1904. Serial No. 227,108.

To all whom it may concern:

Be it known that I, EDWARD W. SMITH, a citizen of the United States, and resident of Philadelphia, in the county of Philadelphia 5 and State of Pennsylvania, have invented a certain new and useful Constant-Level Device for Storage Batteries, of which the following is a specification.

The changing density of the electrolyte due 10 to charge and discharge of a storage battery is a guide or indication of its workings. Provisions have been suggested for eliminating from consideration such density changes as are due to different temperatures, and

15 It is one object of the present invention to provide for eliminating another source of error or inaccuracy which would arise by reason of evaporation.

Another object of the invention is to provide 20 for automatically maintaining a constant level of the electrolyte.

Another object of the invention is to provide 25 a comparatively simple and satisfactory piece of apparatus for automatically introducing so much fluid to the electrolyte as is necessary to keep the same at a constant level.

To these and other ends hereinafter set forth the invention comprises the improvements to be presently described and finally claimed.

The nature, characteristic features and scope of the invention will be more fully understood from the following description 35 taken in connection with the accompanying drawings forming part hereof and in which

Figures 1 and 2 are side views partly in section of apparatus embodying features of the invention and illustrating respectively the 40 movable parts of the apparatus in different positions, and Fig. 3, is a view principally in elevation showing the apparatus in application to a cell.

In the drawings 1, is a tube provided at its 45 lower end with an outlet 2. Intermediate of the ends of the tube, but so as not to communicate with the interior thereof there branches a support 3 enlarged at its upper end 4 for the reception of a closure 5. This 50 support is provided with an inlet 6 which communicates with its interior.

7, is a U-shaped tube one end of which penetrates the closure 5 and the other end of which depends or projects downward into 55 the top of the tube 1. As shown, this de-

pending end 8 is tapered and constitutes a valve seat.

9, is a sleeve slidable on the tube 1 and at its upper end it is provided with a stoppered depression 10, which constitutes a valve arranged to coöperate with the seat on the end 8 of the tube. The walls of this depression are perforated as indicated at 11. The parts 3 and 7 taken together constitute what may be termed a goose-neck. The sleeve 9 is provided with downwardly curved depending arms 12 which terminate in floats 13.

The whole instrument is well adapted to be made of glass, though not necessarily constructed of that material.

In use the described instrument is arranged preferably, in what is called a pilot cell, that is to say, one of the cells of the battery, typical of the others and well adapted for purposes of observation, for example, by applying to it 75 suitable instruments for measuring changes in the density of its electrolyte and making such corrections as may be necessary for determining only those changes in the electrolyte which are due to the workings of the battery. The tank 14 and plates 15 may be assumed to be parts of such a pilot cell. The tube 1 is arranged in the pilot cell so that the outlet 2 is near the bottom of the electrolyte 80 16 in the cell. The purpose of this is that 85 water or other fluid introduced to maintain the level of the electrolyte constant should be introduced at the bottom, otherwise it will not be properly diffused. The tube 1 may be supported in vertical position in any convenient way. As shown a projection on it is 90 illustrated as resting upon the tops of the plates. Of course the floats 13 must be buoyed by the liquid. The inlet connection is placed in communication with a suitable 95 source of supply. Should water evaporate from the electrolyte 16, it is obvious that its density would increase and such increase would interfere with the ascertainment of 100 density changes due to the workings of the battery. However, evaporation of the electrolyte would cause the floats to fall with the result that water would enter by way of 6, 7, 105 past the apertures 10 and through the tube 1, so as to compensate for loss by evaporation. As soon as the proper level had been reached the floats would rise lifting the sleeve 9 and valve 10, thus closing the escape from the U-shaped tube and cutting off the supply 110 of fluid. In this way the level of the elec-

trolyte in the cell is kept substantially constant.

It will be obvious to those skilled in the art to which my invention relates that modifications may be made in details without departing from the spirit thereof, hence the invention is not limited further than the prior state of the art may require, but

Having thus described the nature and objects of my invention what I claim as new and desire to secure by Letters Patent is

1. The combination of a storage battery tank containing electrolyte and from the top of which water evaporates, a water supply, a tube arranged to discharge water from the supply to near the bottom of the electrolyte, and a float device including a valve for normally separating the water supply and electrolyte to prevent their commingling and said valve adapted to open only when the level of the electrolyte falls.

2. A storage battery electrolyte constant level device comprising a tube having an outlet at or near its lower end and a support branching from its intermediate portion, an inlet communicating with the support, a

closure for the support, an inverted U-shaped tube penetrating the closure and dipping into the upper end of the tube, a sleeve slideable on the tube and provided at its upper end with a depression constituting a valve for the end of the U-shaped tube and having a perforated wall, and arms branching from the sleeve and respectively provided with floats, substantially as described.

3. A storage battery electrolyte constant level device comprising a tube having an outlet at or near one end and provided with a goose-neck arranged to discharge into the other end, inlet connections through the goose-neck, and a sleeve slideable on the tube and provided with a float device, and with valve means for opening and closing the goose-neck inlet connections, substantially as described.

In testimony whereof I have hereunto signed my name,

EDWARD W. SMITH.
